UNITED STATES PATENT OFFICE.

EDWARD W. BURGESS, OF MILWAUKEE, WISCONSIN.

INTERLOCKING TILE SLAB.

Application filed April 17, 1922. Serial No. 554,036.

To all whom it may concern:

Be it known that I, EDWARD W. BURGESS, a citizen of the United States, and a resident of the city of Milwaukee, county of Milwaukee, and State of Wisconsin, have invented certain new and useful Improvements in Interlocking Tile Slabs; and I do declare the following to be a clear, exact, and complete description thereof, such as will enable persons skilled in the art to which the invention relates to make and use the same, reference being had to the accompanying drawings as showing some constructional forms in which my invention has been embodied.

The invention relates to cast or moulded concrete slabs, designed for use in forming the floors as well as the roofs of structural steel frame and other buildings.

Precast concrete tile slabs, by reason of the convenience with which they may be installed in position, have largely superseded concrete surfaces cast in place to form roof decks, and are also being used in the construction of floors. In addition to the convenience which inheres to their ready installation in position, there resides a great economy in the manufacture of tiles of the desired dimensions over the older practices of building forms and boxes to support the concrete mixtures heretofore used in constructing floor and roof sections of larger areas.

As indicated above, precast tile have come into general use, having been found to possess extreme serviceability. These precast tile are made of rectangular sections for short spans, and of channel type sections for longer spans. In roof structures they are laid directly on the purlins or trusses, with the joint sealed with elastic cement, and covered with suitable roof material.

In recognition of the fact that a concentrated load upon one of the tile will serve to deflect the same somewhat from its normal plane, attempt has been made to interlock the tile at their abutting edges, so that a distribution of the load imposed upon any one of the tile will be effected and placed upon the adjacent tile, by virtue of such interlocking means. Such interlocking means have been permanent in form, and have necessitated destruction of the tile when it was desired to remove any of the same.

My present invention involves the formation with interlocking means which are permanent in character so long as the roof or

floor is not disturbed. But in my invention, the interlocking means may be easily withdrawn when desired, thus permitting the removal from its position in the floor or roof of any tile, and without injury to the same. The tile so removed may be restored to its position if desired, and again interlocked to the adjoining tile in an exceedingly simple and efficient manner. The advantages of my invention are particularly manifest in the floors of buildings constructed for manufacturing purposes, wherein it is necessary to make openings through the floors for the installation of machinery and other equipment, after the completion of the building. Openings may be made where desired, and closed with equal facility when no longer needed, and this may be accomplished without affecting the integrity of the floor structure after restoration thereof has been made.

In carrying out my invention, I cast in the edges of the tile, diagonal slots which register in the adjacent tile when placed in position. Into the registering slots thus formed I drive keys of suitable material having a width sufficient to fill the slots, a single key thus engaging and mutually supporting the adjacent tile. By reason of the angular arrangement of the keys in the slots, a load resting upon one tile is thereby distributed to the contiguous tile. When it is desired to remove a tile it is necessary only to drive the key out of slots. The tile then being no longer interlocked with the adjacent tile, may readily be lifted from its position. In the event of restoration of the tile to its former position to close the opening, it will be necessary only again to insert keys to restore the surface to its prime condition.

In the drawing which accompanies this specification, and in the latter, I have shown and described some specific forms in which the invention has been embodied. But I do not limit the scope of my invention to what is shown and described, inasmuch as my invention resides broadly in interlocking adjacent tile by means of keys entered in diagonal slots or channels formed in the edges of the tile, whereby any load resting upon one tile is distributed to the adjacent tile through such interlocking provisions, and permitting the easy removal of a tile by simply withdrawing the interlocking key.

In the drawings which accompany this specification;

Figure 1 is a plan view showing a grouping of two tile as assembled in a floor or roof section, and showing the manner in which the interlocking is effected.

5 Fig. 2 is a perspective view of the same.

Fig. 3 is an edge view showing in elevation one of the tile shown in Figs. 1 and 2.

Fig. 4 is a similar view showing the tile as provided with an increased number of 10 slots for effecting the interlocking in a larger degree.

Fig. 5 is a like view of a modification which will be described hereinafter.

In the drawing, the numerals 10 indicate 15 precast concrete tile slabs, serviceable in the formation of both floors and roofs. In casting or moulding such tile I create inclined or diagonal slots 11, which are uniformly formed, at predetermined points in the side 20 edges of the tile, so that in whatever position the tile may be assembled between the girders or purlins, the said slots will register in the adjacent tile. After the tile have 25 been laid I drive into the diagonal slots keys or splines 12 which are of sufficient dimensions to entirely fill the slots and be retained therein by frictional engagement. The length of the keys 12 should be about equal to that of the diagonal slots in which they 30 are inserted; and they should be driven into position so that their upper ends will be flush with the surface of the tile.

These keys 12 may be of any suitable material, such as metal or hard wood, or they 35 may be formed in some cases of concrete either precast and grouted in place, or poured in.

In some instances, referring to Fig. 5, it 40 may be desirable to extend the slot only partially across the edge of the tile, so as to leave the lower face of the tile unbroken as at 13. In such constructions the keys will be of appropriate length. In arranging for the removal of a tile of either class it is 45 necessary only to drive the keys through from the upper surface, whereupon the particular tile may be lifted from its place. The openings formed on the opposite edges of the tile by the dislodgment of the keys 50 affords a means for engaging the tile with suitable appliances to lift it from its position.

The construction in which my invention is used is superior in strength to the ordinary 55 arrangement in which the interlocking of the tile slabs is effected by the use of tongues and grooves extending longitudinally of the tile, or otherwise. In all of such older constructions, the shearing strength of the concrete is much less than one half of the depth 60 of the tile. In my improved construction however, a much greater and maximum shearing strength of the concrete is attained, due to the diagonal bearing which extends 65 over the full depth of the tile. The slots 11

are so located that a vertical line running from one slot will not intersect another.

It will be apparent that the diagonal arrangement of the interlocking means will serve to maintain the tile slabs in one plane 70 when a load is placed thereon, the deflection of one tile under such load being transmitted to the adjoining slabs and the weight of the load distributed over the immediate area until the pressure is equalized. 75

The interlocking provisions on the edges of the tile slabs may be one or a plural number, determined by the length of the tile slabs, as required by the particular construction in which such tile slabs are to be used. 80

Having thus described my invention, what I claim and desire to secure by Letters Patent of the United States, is:

1. Interlocking tile slabs formed with diagonal slots in their opposite edges, in 85 combination with keys filling the registering slots of adjacent tile slabs, whereby a weight imposed upon one tile slab is distributed through such keys to the adjacent tile slabs. 90

2. A floor structure composed of precast tile slabs, the abutting edges of which are provided with diagonally extending registering slots, in combination with keys filling the slots, whereby a weight imposed upon one of the tile slabs is distributed through the said keys to the adjoining tile slabs. 95

3. Interlocking tile slabs, the abutting edges of which are formed with diagonally 100 extending registering slots, in combination with removable keys in the said slots and serving to maintain the tile slabs in the same plane when a load is imposed upon one of them. 105

4. A precast concrete tile slab adapted to be supported at its ends and formed with diagonal slots or grooves in its edges for the reception of a key to interlock it with an adjoining tile slab. 110

5. A floor structure comprising precast tile slabs each of which is provided in its edges with diagonal slots for the reception of keys to interlock adjoining tile slabs, such keys being removable from the slots to permit a tile slab to be removed from the floor without damage to the tile slab. 115

6. A floor structure comprising precast tile slabs each of which is formed in its edges with means for distributing the weight 120 imposed on one tile to the adjoining tiles, in combination with removable keys interlocking the said means on abutting tile slabs.

In testimony whereof, I have signed my name at Milwaukee, this 13th day of April, 125 1922.

E. W. BURGESS.

Certificate of Correction.

It is hereby certified that in Letters Patent No. 1,485,068, granted February 26, 1924, upon the application of Edward W. Burgess, of Milwaukee, Wisconsin, for an improvement in "Interlocking Tile Slabs," an error appears requiring correction as follows: In the drawing strike out Figure 6; and that the said Letters Patent should be read with this correction therein that the same may conform to the record of the case in the Patent Office.

Signed and sealed this 26th day of May, A. D. 1925.

[SEAL.]

KARL FENNING,
Acting Commissioner of Patents.
